VENDING MACHINE CABINET

Burgess C. Case, Plainfield, N. J.

Application November 28, 1947, Serial No. 788,525

6 Claims. (Cl. 312—219)

1

The present invention relates to the construction of vending machine cabinets, and more particularly, to the construction of the cabinet locking mechanism for coin operated vending machines requiring periodic restocking, preferably from a location at the front of the machine.

In coin operated vending machines, such as the automatic corn popping machine disclosed in my copending joint application Serial No. 786,190, filed November 15, 1947, the machine is preferably operated by a customer inserting a coin through a coin slot in the front of the machine. For that reason, such machines are often positioned in locations at the points of use where they are readily accessible only from the front of the machine. Accordingly it is advantageous to provide also for access to the coin receptacle within the machine and to the internal tanks containing the raw corn and cooking compound through closures operable from the front of the machine. Repair and replacement of the machine operating mechanism is occasionally necessary and for this purpose a door is provided in the rear of the machine, through which the mechanism can be withdrawn.

The general object of the invention is the provision of a vending machine cabinet of the character described having an improved closure locking system operable only from the front of the machine. A more specific object is the provision of a cabinet hinged top and front door construction which prevents opening of the top while the door is closed. A further specific object is the provision of a cabinet having a plurality of closures controlled by a single key-operated lock.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a front elevation of a coin-operated vending machine cabinet constructed in accordance with my invention;

Fig. 2 is a vertical section taken on the line 2—2 of Fig. 1;

Fig. 3 is a vertical section through the front door locking system;

Fig. 4 is a horizontal section taken on the line 4—4 of Fig. 2;

Fig. 5 is an elevation of the inside of the rear wall of the cabinet;

Fig. 6 is a horizontal section taken on the line 6—6 of Fig. 5;

Fig. 7 is an enlarged elevation of one of the rear door locking devices; and

Figs. 8, 9 and 10 are sections taken on the lines 8—8, 9—9, and 10—10 respectively of Fig. 7.

2

The automatic coin operated corn popping machine illustrated in the drawings as one embodiment of the invention has a sheet metal cabinet 20 of general rectangular vertical and horizontal cross-section, provided with a front door 21, a rear door 22 and a hinged top 23. A coin slot 24 is located in the front of the cabinet. The front door has a piano type hinge 25 along one vertical side and cut outs for windows 26 and 27, a bag receiving compartment 28, and a bag slot 29. The front door is rearwardly inclined, as shown in Fig. 2, so that its front side projects beyond the adjacent front wall portions of the cabinet. The door sides 21^a extend rearwardly to the plane 15 of the cabinet. The rear door 22 has a vertical piano hinge 31 along one vertical side and is arranged in the plane of the cabinet rear wall. The cabinet top 23 has a horizontal hinge 32 on its rear side.

20 In the machine described, the front door 21, rear door 22, and top 23 constitute all of the movable closures permitting access to the interior of the machine, the front door permitting front access to the coin receptacle and operating mechanism, the top permitting access to the raw corn and cooking compound tanks which have removable top covers, and the rear door used for rear access to and removal of the operating mechanism.

25 30 For the purpose of sanitation and safety, it is important that unauthorized persons be prevented from having access to the interior of the machine. In accordance with the invention, the cabinet is provided with closure locking provisions controlled from a single key-operated barrel type lock 35 on the free side of the front door. The lock controls a locking mechanism on the inner side of the front door side 21^a consisting of an arm 36 secured to the lock barrel and having a hook-shaped end 37 engaging a stud 38 on the upper end of a vertically movable lock slide bar 40. As shown in Figs. 2—4, the slide bar 40 is slideably mounted on an inverted vertical channel member 41 secured to the door side 21^a. The channel member has three vertical slots 42, 43 and 44 therein through which project studs 45, 46 and 47 respectively carried by the slide bar. The studs 45 and 47 are mounted as shown in Fig. 4 so as to extend on opposite sides of the slide bar 40, the outer portion of the studs extending through the channel member slot having a washer 49 thereon to hold the slide bar in position. The inner portions of the studs 45 and 47 are arranged to fit into grooves 50 formed in

45 50 the upper edges of the brackets 51 and 52 respectively mounted on the side walls of the cabinet adjacent the bottom and top of the front door respectively, as shown in Figs. 2—4. The inner portion of the center stud 46 terminates at the slide bar and this stud serves as a guide only. With the described arrangement the front door can be firmly locked to the cabinet and readily opened when access is desired.

The locking mechanism for the rear door 22 is mounted at the inner side thereof and is operable only if the front door is first opened. As shown in Figs. 5-10, the rear door locking mechanism consists of a pair of lift latches 60 and 61 pivoted on guide brackets 62 and 63 respectively mounted on the cabinet rear wall adjacent the upper and lower ends respectively of the door. The latches 60, 61 are bent to engage grooved brackets 65 and 66 respectively secured to the rear door adjacent the guide brackets 62 and 63. The latches are simultaneously actuated by a connecting link 68 and an extension of the upper latch 60 to form a handle 69.

The hinged top is locked in its closed position by means of an L-shaped metal strip 70 extending along and secured to the front edge of the top. The strip has a downwardly curved forwardly projecting portion 71 arranged to fit snugly within the curved upper edge of the front door 21, so that the top cannot be raised until the front door is opened. The top can be held in its open position when desired by an arm 74 pivoted on one lower side edge of the top. The arm is arranged to ride on a bracket 75 projecting from the side wall of the cabinet, and a notch 76 in the arm hooks in the bracket 75 when the top is raised, as indicated in broken lines in Fig. 2.

The locking system described provides a simple, but effective, protective construction for the movable closures of the vending machine, insuring access to the interior of the machine only by an authorized person. It also permits the daily servicing of the machine to be readily carried out from the front of the machine, adding to the convenience and speed of servicing.

While in accordance with the provisions of the statutes I have illustrated and described herein the best form of the invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. A vending machine cabinet having front, rear and side walls, a side-hinged bulging front door mounted on and projecting beyond the cabinet front wall, a stationary bracket within said cabinet and having a grooved portion projecting beyond the cabinet front wall, a locking bar vertically slideable on the inner side of the projecting portion of said front door and having a projecting stud arranged to fit into said grooved bracket, and a rotary lock in said front door having an operative connection with said locking bar.

2. A vending machine cabinet having front, rear and side walls, a side-hinged bulging front door mounted on and projecting beyond the cabinet front wall, a pair of vertically spaced stationary brackets mounted on a cabinet side wall and having a grooved portion projecting beyond the cabinet front wall, a locking bar vertically slideable on the inner side of the projecting portion of said front door and having a pair of projecting studs arranged to fit into corresponding grooved brackets, and a rotary lock in said front door having an operative connection with said locking bar.

3. A vending machine cabinet having front, rear and side walls, a side-hinged bulging front

door mounted on and projecting beyond the cabinet front wall, a pair of vertically spaced stationary brackets mounted on a cabinet side wall and having a grooved portion projecting beyond the cabinet front wall, a locking bar vertically slideable on the inner face of the free side of the projecting portion of said front door and having a pair of projecting studs arranged to fit into corresponding grooved brackets, and a rotary lock in said front door having an operative connection with said locking bar.

4. A vending machine cabinet having front, rear and side walls, a side-hinged bulging front door mounted on and projecting beyond the cabinet front wall, a top closure for said cabinet hinged at its rear end and having its front end projecting into the upper end of said front door, a stationary bracket within said cabinet and having a grooved portion projecting beyond the cabinet front wall, a locking bar vertically slideable on the inner side of the projecting portion of said front door and having a projecting stud arranged to fit into said grooved bracket, and a rotary lock in said front door having an operative connection with said locking bar.

5. A vending machine cabinet having front, rear and side walls, a side-hinged bulging front door mounted on and projecting beyond the cabinet front wall, a top closure for said cabinet hinged at its rear end and having its front end projecting into the upper end of said front door, a pair of vertically spaced stationary brackets mounted on a cabinet side wall and having a grooved portion projecting beyond the cabinet front wall, a locking bar vertically slideable on the inner face of the free side of the projecting portion of said front door and having a pair of projecting studs arranged to fit into corresponding grooved brackets, and a rotary lock in said front door having an operative connection with said locking bar.

6. A front accessible vending machine cabinet having front, rear and side walls, a side hinged bulging front door mounted on and projecting beyond said front wall, a door in said rear wall, a rearwardly hinged top, a locking lever for said rear door operable only from the inner side of said rear door, the rear upper edge of said front door being arranged in overlapping contact with the front edge of said top when closed, a pair of vertically spaced stationary brackets mounted on the side wall of the cabinet at the free side of said front door and having a grooved portion projecting beyond the cabinet front wall, a locking bar vertically slideable on the inner face of the free side of the projecting portion of said front door and having a pair of projecting studs arranged to fit into corresponding grooved brackets, and a rotating lock on the free side of said front door and having an offset portion operatively connected to said locking bar.
